UNITED STATES PATENT OFFICE.

DONALD T. HASTINGS, OF DETROIT, MICHIGAN, ASSIGNOR TO HUPP MOTOR CAR COMPANY, OF DETROIT, MICHIGAN, A CORPORATION OF MICHIGAN.

LAPPING-MACHINE.

1,139,520.

Specification of Letters Patent. Patented May 18, 1915.

Application filed June 15, 1914. Serial No. 845,272.

To all whom it may concern:

Be it known that I, DONALD T. HASTINGS, a citizen of the United States of America, residing at Detroit, in the county of Wayne 5 and State of Michigan, have invented certain new and useful Improvements in Lapping-Machines of which the following is a specification, reference being had therein to the accompanying drawings.

10 My invention relates to a machine for lapping the engaging surfaces of relatively-movable members.

The invention has among the objects thereof to provide a device that will efficiently lap the engaging surfaces of relatively-movable members while such surfaces are in engagement with each other; to provide a device that will effect a proper movement between the relatively-movable members for best producing an efficient lapping; to provide a structure by which a series of relatively-movable members may be lapped; to provide a device in which any wear that may occur between the parts of the lapping 25 machine will not affect the accuracy of the surfaces being lapped; further, to provide a machine which does not require special skill on the part of the operator. Other objects of the invention will more fully hereinafter appear.

30 The invention resides in the peculiar construction, arrangement and combinations of parts as hereinafter set forth.

While a machine embodying my invention 35 is adapted for other purposes, it is especially useful for lapping piston rings in their own cylinders. The invention will, therefore, be illustrated and described as embodied in a machine for lapping piston 40 rings.

In the drawings,—Figure 1 is an end elevation, with certain parts in section, of a piston ring lapping machine embodying the invention, showing the pistons and cylinders in operative relation thereto; Fig. 2 is a sectional side elevation with the connecting rods removed; Fig. 3 is a top plan view; Figs. 4 and 5 are side and end elevations respectively of the connecting rod; 45 and Fig. 6 is a detail view showing the interior of an oscillatory casing containing a pawl and ratchet mechanism. Fig. 7 is a diagrammatic illustration of the paths of two points during the lapping operation;

and Fig. 8 is a detail view of a crank disk 55 and certain parts immediately associated with the same.

With my improved device, after the rings have been engaged with the piston, the piston is inserted within the cylinder and connected to the lapping machine, the latter effecting the reciprocation of the piston in the cylinder. If the piston were given reciprocatory action only, there would be a tendency for sharp projections on one of the 65 surfaces being lapped to groove the other surface. My improved machine, therefore, is so constructed as to cause a rotary, as well as a reciprocatory, movement to be given to the piston. Preferably the piston is so actuated as to cause points thereupon to trace intersecting paths upon the cylinder wall.

While various devices differing in details of construction might be employed for accomplishing the result desired, I have illustrated herein the preferred form of a machine embodying the invention, though I do not desire to limit the protection to the particular structure illustrated.

Referring to the drawings, A designates 80 a suitable support or bed, and B the lapping machine mounted thereupon. The latter comprises a suitable frame, herein shown as composed of spaced uprights D E having feet F bolted to the bed B. Intermediate 85 the ends of the uprights are shouldered portions G to which are secured as by bolts H, cross-bars I. J is a shaft having the ends thereof extending through bearings L in the uprights and threaded to receive clamping 90 nuts M.

Upon the shaft J is journaled a rocking frame, which in the structure illustrated is composed of spaced beams N and O, having bearing portions P journaled upon the shaft 95 J and carrying at their outer ends two series of bearings Q. Within the bearings Q are journaled shafts R, the lower end of each of which is provided with an enlarged bifurcated bearing S that forms a part of a universal connection T between the shaft R and a connecting rod U. The number of bearings of each series may be varied as desired, depending upon the number of pistons to be lapped in one operation. The connecting 100 rod U preferably is composed of a pair of members V and W pivotally connected intermediate their ends as at X. The upper

ends of these members are shaped to form a bifurcated portion Y having alined bearings Z for receiving a pin A' that forms a part of the universal joint U. At the lower ends 5 of the members V and W are substantially semi-cylindrical bearings B' for engaging the piston pin and within which the latter is adapted to journal. Each of these bearings is pivotally attached to its respective member by means of a headed stud C'. There is, 10 therefore, a universal connection between the piston D' and the connecting rod, as well as between the latter and the shaft R. In order to avoid too tight an engagement between 15 the piston pin and the bearings B' the members V and W are provided with abutting stops E' that limit the movement of the bearings toward each other.

The rocking frame may be actuated in 20 any suitable manner, but in the structure shown the members N and O carry brackets F' to which is attached a rod or shaft G'. H' is a bearing journaled upon the member G' and having a threaded engagement with 25 a rod I'. The lower end of this rod has a threaded engagement with a bearing J' that is journaled upon a pin K' projecting laterally from a crank disk L'. The latter is fixed to one end of a shaft M' that is journaled in bearings N'. To the outer end of 30 the shaft M' is secured a combined fly-wheel and driving pulley O' which is driven from any suitable source of power. In order to permit the length of the rocking movement 35 of the outer ends of the reciprocating frame to be varied to properly regulate the travel of the piston in the cylinder, the pin K' is formed eccentric to the portion A² which is secured to the member L'. Preferably the 40 portion A² is tapered and the opening B² in the member L' also tapered so as to permit of tightly clamping these parts together. The opposite ends of the rod I' are provided with right and left hand threads respectively 45 so as to allow the position of the head relative to the crank disk to be varied.

As before stated, it is desirable during the lapping to turn the piston within the cylinder, and while various turning movements 50 may be employed for accomplishing the desired end, preferably in one direction of reciprocation the piston moves in a straight path, while during the opposite direction of reciprocation the piston is turned a fraction 55 of a revolution, which will cause the curved paths to intersect the straight. In the construction illustrated the shafts R of each series are intermittently rotated, and as the devices for turning the shafts R of both 60 series are alike, a detail description of such mechanism of one series only will be given. Thus, keyed to the shafts R are gears P', the gears of adjacent shafts intermeshing, while one of the shafts, preferably an outer 65 member of the series, is provided with a

ratchet wheel Q' fixed thereto. This ratchet wheel has a series of recesses C² herein shown as 120° apart. R' are dogs of a rockable member S' which are adapted to engage the notches in the ratchet wheel. S² is a laterally-extending arm on the member S' connected by a universal joint T' to an arm U'. The other end of the arm U' is pivotally connected as at V' to a bracket W' on the upright E. The arrangement is such that upon the rocking of the movable frame in one direction the member S' will be moved to position the dogs to engage the notches of the ratchet wheel, while upon rocking of the frame in the opposite direction, one of the dogs will engage a notch on the ratchet wheel and cause a turning of the shaft R to which the ratchet wheel is connected. This—through the medium of the intermeshing gears—will cause a corresponding turning of the remaining shafts R. The turning of the shafts R will of course, 70 rotate the connecting rods and, therefore, turn the pistons within the cylinders, the turning of the pistons taking place during 75 movement of the piston longitudinally of the cylinder. The ratchet mechanisms of the two series of shafts R are arranged to alternate in rotating the shafts of the two series; that is—upon the upstroke of one 80 series of pistons the latter will be turned, while in the other series the pistons will be turned during the down-stroke.

With the construction described, which is 85 designed for simultaneously lapping the 100 piston rings of two four-cylinder engines, the piston rings are engaged with the pistons and the latter placed in the cylinders. The connecting rods of one series of shafts are engaged with the piston pins and then 105 the cylinder casing is positioned beneath the rockable frame. It is of course, necessary to properly align the cylinders with respect to the connections T and this is 110 preferably accomplished by means of 110 spring-pressed pins a, which are adapted to engage holes b in the cylinder base through which the crank case studs pass, these holes necessarily being accurately located with respect to the cylinder bores. The cylinder 115 is clamped to the bed by means of a set-screw A³ carried by the main frame and adapted to engage the cylinders. The connecting rods are then attached to the shafts R by means of the pins A'. After the two 120 sets of pistons are so engaged with the rockable member, power is applied to the driving mechanism, which will cause a rocking of the frame. Upon the rocking of the frame carrying the series of shafts, the pistons are reciprocated in their cylinders, and during the reciprocation the ratchet mechanism will—as before stated—effect in one 125 direction of movement a turning of the pistons within the cylinders. For instance, the 130

cylinders attached to one series of shafts R travel in a straight path upon the downward movement, and upon the upward movement are gradually turned through an arc of 120° , while the pistons attached to the other series of shafts travel in a straight path upon the upward movement and are turned during the down-stroke. This will cause the curved paths to intersect the straight path's revolutions, as will be readily seen upon reference to the diagram of Fig.

7. In this diagram the line designated by "1" indicates the path of movement of a point on the piston ring during one revolution, while the line designated by "2" indicates the path of movement of another point during the same revolution.

When the machine is first started, preferably kerosene is applied to the surface of the piston and after the machine has been in operation for about three to five minutes, a suitable lapping paste, such as ground glass and kerosene paste, is applied at intervals of from three to five minutes. This paste is applied as by means of a brush to the skirt of the piston when the latter is at the top of the stroke. However, any suitable oil, lapping paste or the like may be employed, and the quantity and manner of application varied as desired.

A machine embodying my invention provides for very high efficiency, since while the piston rings of the pistons for two engine casings are being lapped within their cylinders, the operator may assemble the piston rings of the pistons for two other sets of engine casings. Furthermore, since the connecting rod is provided with universal joints at opposite ends thereof, any tendency to produce a binding action of the pistons or their rings against the walls of the cylinder is eliminated, and even if wear occurs between the parts of the lapping machine, it would have no effect in producing the proper travel of the piston in its cylinder.

While I have shown and described the preferred embodiment of my invention, I do not, as hereinbefore stated, desire to limit the protection to the particular structure illustrated.

What I claim as my invention is:—

1. The combination with relatively-movable members, of means for lapping said members, comprising means for relatively moving said members to cause points upon one of said members to trace intersecting paths in relation to the other member.

2. The combination with relatively-movable members having contiguous surfaces, of means for lapping said members, comprising means for effecting a relative movement between said surfaces in transverse directions.

3. The combination with relatively-movable members having contiguous surfaces, of means for lapping said members, comprising

means for effecting a relative reciprocatory and rotary movement between said surfaces.

4. The combination with relatively-movable members having constant engagement, of means for lapping said members, comprising means for effecting a continuous relative reciprocation between said members, and means for producing a predetermined rotary movement during a portion of the reciprocatory movement.

5. The combination with relatively-movable members having constant engagement, of means for lapping said members, comprising means for effecting a continuous relative reciprocation between said members, and means for automatically effecting a predetermined rotary movement during a portion of the reciprocatory movement.

6. In a lapping machine, a rocking frame, means for rocking said frame, a work-engaging member carried by said frame, and means for transmitting to said work-engaging member a predetermined rotary movement.

7. In a lapping machine, a rocking frame, a plurality of work-engaging members carried by said frame, and means for automatically transmitting to said work-engaging members a corresponding rotary movement.

8. In a lapping machine, the combination with a vertically swinging work-engaging member, of means for uniformly reciprocating said member, and means for imparting a turning movement to said member.

9. In a lapping machine, the combination with a work-engaging member, of means for uniformly reciprocating said member, and means for imparting a predetermined and intermittent rotary movement to said member.

10. In a lapping machine, the combination with a main frame, a work-engaging member, means on said frame for uniformly reciprocating said member, and means for imparting to said member a predetermined rotary movement.

11. In a lapping machine, a rocking frame, a work-engaging member carried by said frame, means for rocking said frame, and means for producing an intermittent rotation of said member during the rocking of said frame.

12. In a lapping machine, a main frame, a rocking frame journaled thereon, means for rocking said last-mentioned frame, a bearing carried by said last-mentioned frame, a shaft journaled in said bearing, a work-engaging member pivotally engaging said shaft and adapted to be reciprocated upon the rocking of said frame, and means for effecting a turning of said shaft.

13. The combination with a plurality of series of relatively-movable members, of means for automatically lapping said series.

14. In a lapping machine, a rocking frame, work-engaging means carried by and adapted to be rocked with said frame, and means for intermittently rotating said work-engaging means.
15. In a lapping machine, a rocking frame, work-engaging means, a universal connection between said work-engaging means and said frame, and means for intermittently rotating said work-engaging means.
16. In a lapping machine, a rocking frame, a shaft carried by said frame, means for intermittently rotating said shaft, an arm, and a pivotal engagement between said arm and said shaft.
17. In a lapping machine, a rocking frame, a shaft carried by said frame, means for intermittently rotating said shaft, an arm, and a universal connection between said arm and said shaft.
18. In a lapping machine, a main frame, a rocking frame journaled thereon, means for rocking said last-mentioned frame, a plurality of bearings carried by said rocking frame, shafts journaled in said bearings, intermeshing gears upon said shafts, means for intermittently rotating one of said shafts, and a plurality of work-engaging arms carried by said shafts.
19. In a lapping machine, the combination of a frame, means for alining the work in relation to said frame, work-engaging means, and means for imparting a reciprocatory and rotative movement to said work-engaging means.
20. In a piston ring lapping machine, the combination of a main frame, a rocking frame journaled thereupon, means for rocking said rocking frame, two series of bearings carried by said rocking frame upon opposite sides of the fulcrum thereof, shafts journaled in the bearings of each series, a ratchet mechanism associated with one shaft of each series, a connection between said ratchet mechanism and the main frame for intermittently actuating the ratchet mechanism upon a rocking of the rocking frame, intermeshing gears upon the shafts of each series whereby intermittent rotative movement of the ratchet is transmitted to all of said shafts, arms carried by the lower ends of the shafts of each series, a bearing at the lower end of each arm for engaging the piston pin, and cylinder-alining means carried by the main frame.
21. In a lapping machine, the combination with a rocking arm, an intermittently rotated shaft carried by said arm, work-engaging means, a universal joint connection between one end of said work-engaging means and said shaft, and separable bearings at the other end of the said work-engaging means, for the purpose described.
22. In a lapping machine, the combination of a rocking frame, an arm adapted to be rocked by said frame, means for intermittently rotating said arm, said arm comprising a pair of members pivotally connected together intermediate their ends, complementary bearing blocks pivotally secured to the corresponding ends of said members, and stops upon said members limiting the movement of said bearings toward one another.
23. In a lapping machine, the combination with a main frame, of a rocking frame mounted thereupon, a work-engaging member reciprocated by the rocking frame, and means utilizing the relative motion of the main frame and rocking frame to rotate the work-engaging member.
24. In a lapping machine, the combination with a main frame, of a rocking frame mounted thereupon, a shaft carried by the rocking frame, a work-engaging member actuated by said shaft, and a connection between the main frame and said shaft utilizing the relative motion of the main frame and rocking frame to rotate said shaft.
25. In a lapping machine, the combination with means for supporting an engine cylinder, of a member for engaging a piston within said cylinder, and means for automatically actuating said member to lap the piston with the cylinder.
26. In a lapping machine, the combination with means for supporting an engine cylinder, of a member for engaging a piston within the cylinder, and means for simultaneously rotating and reciprocating said member to lap the piston with the cylinder.
- In testimony whereof I affix my signature in presence of two witnesses.
